UNITED STATES PATENT OFFICE.

THOMAS E. NORMAN, OF FALL RIVER, MASSACHUSETTS, ASSIGNOR TO DRAPER CORPORATION, OF HOPEDALE, MASSACHUSETTS, A CORPORATION OF MAINE.

FILLING-REPLENISHING LOOM.

Application filed January 24, 1923. Serial No. 614,541.

To all whom it may concern:

Be it known that I, THOMAS E. NORMAN, a citizen of the United States, residing at Fall River, in the county of Bristol and 5 State of Massachusetts, have invented an Improvement in Filling-Replenishing Looms, of which the following description, in connection with the accompanying drawings, is a specification, like characters on the drawings representing like parts.

This invention relates to filling replenishing looms wherein the filling in the running shuttle is replenished when the filling fails to be laid in the shed on a detecting 15 beat.

In that type of filling replenishing looms where a fresh supply of filling is furnished when that in the active shuttle becomes entirely exhausted or broken, it has been proposed heretofore to provide a detecting mechanism at one side of the loom for replenishing the filling on detection of filling absence, and another detecting mechanism on the opposite side of the loom for controlling the action of the replenishing detector or effecting loom stoppage in case filling is exhausted on a predetermined number of detecting beats. In this type of filling replenishing looms, however, the loom has been brought to rest heretofore with the shuttle in the non-replenishing box, with the result that the weaver is called upon to remove the shuttle from the non-replenishing box, supply it with a fresh filling carrier, thread the shuttle and start the loom. The delay in carrying these operations out manually by the weaver has materially lessened the output of the loom and has thrown upon the weaver many added 40 duties.

One of the objects of the present invention is to provide a filling replenishing loom of the type referred to wherein upon a succession of filling failures or detections 45 of filling absence by the stopping detector, the loom may be brought to rest with the shuttle in the replenishing box and the replenishing mechanism itself positioned to effect a transfer of the filling automatically to the shuttle upon the first beat-up movement of the lay following loom stoppage.

Another object of the present invention is to provide a filling replenishing detector 55 at the non-replenishing side of the loom.

and a stopping detector at the replenishing side of the loom which may be readily changed to effect loom stoppage on the occurrence of two or more absences of filling by the stopping detector with the shuttle in 60 the replenishing box and the filling replenishing mechanism positioned to effect transfer when the loom is again started.

A good practical form of the invention is shown in the accompanying drawings, 65 wherein:

Fig. 1 is a front perspective view of a filling replenishing loom containing the present invention, certain parts of the loom being broken away for clearness of illustration;

Fig. 2 is an enlarged detached perspective view showing the stopping detector and means for suspending take-up when filling failure is indicated by either the replenishing or stopping detector;

Fig. 3 is an enlarged perspective view of portions of the stopping detector with the parts in separated relation to show more clearly the means for changing the 80 time of operation of the stopping detector; and

Fig. 4 is an enlarged detached side elevation of the stopping detector mechanism in the position the parts occupy to stop the loom following detection of filling absence by the stopping detector.

It has not been deemed necessary herein to illustrate and describe in detail the filling replenishing mechanism except in so far 90 as it is controlled by the replenishing detector, because such replenishing mechanism may be of any usual and well-known type.

In the present instance of the invention 95 the loom frame 1 has mounted at one side thereof the hopper or magazine stand 2 which supports a rotary hopper 3 containing filled carriers or bobbins 4, and as usual in this type of hopper or magazine mechanism the filling carriers are presented in position for transfer by means for giving the rotary hopper rotary movement from time to time as the filling carriers are transferred. These details, however, form 100 no essential part of the present invention, and being well understood by those skilled in the art, further illustration or description thereof is not deemed necessary.

The lay 5 at one side has the non-replen- 110

ishing shuttle box 6 which may be of usual construction, and at the opposite side of the loom the lay is provided with the filling replenishing shuttle box 7 which may 5 also be of usual construction to permit the filling carrier in the shuttle to be ejected by the incoming filling carrier under the action of the usual transerrer.

As shown in Fig. 1, the warp threads a 10 extend from the fell of the cloth b rear- 15 wardly through the reed 8 of the lay and the cloth c passes frontwardly over the breast beam 9 to the cloth take-up roll 10 which may be driven through a train of mechanism from a going part of the loom, such mechanism in the present instance being shown as a series of gears 11, 12, 13 and 14, which are driven step by step through a ratchet wheel 15 mounted on the stud 16, 20 Fig. 2, supported by the loom frame.

The ratchet wheel 15 may be stepped along to effect take-up of the cloth by any suitable mechanism, which in the present instance comprises an arm 17 carrying a take-up pawl 25 18 and given a take-up movement by a going part of the loom, such, for instance, as the lay.

Mounted at the non-replenishing side of the loom is the filling replenishing detector 30 A which, in the present instance, comprises the filling or weft fork 19 pivotally mounted at 20 on a slide 21 and having a front- 35 wardly extending portion 22 for engagement by a hook 23 carried by the weft fork or cam follower 24. The slide 21 is mounted in the stand 25 and its front end bears against a finger 26 which is secured to the transfer shaft 27 carried in bearings of the brackets 28, one at each side of the loom.

The filling replenishing detector may be 40 of usual construction and the transverse or rock shaft 27 is normally under the influence of the usual spring 29 serving to hold the arm 26 against the front of the filling fork slide.

The transfer shaft 27 at the replenishing side of the loom has secured to it an upwardly extending member 30, in the present instance, which is connected by a link 31 to a rocker arm 32, the hub portion 33 of which carries a dog engaging finger 34. The finger 34 is provided with a slot 35 into which projects the pin 36 carried by the transerrer dog 37 which is itself pivotally mounted 55 upon the downwardly projecting portion 38 of the transerrer, which may be of usual construction.

The rocker 32 is connected by a link 39 to the upwardly extending member 40 of a shuttle feeler 41 mounted for rocking movement on the stud or dead shaft 42. The construction is such that should the filling replenishing detector detect the absence of filling on a detecting beat when the shuttle 60 is in the non-replenishing box, the hook 23

of the weft hammer or cam follower will be engaged by the member 22 of the weft fork, and the slide 21 will be moved frontwardly to position the dog 37 of the replenishing mechanism for engagement with the usual bunter on the lay to effect the transfer of a fresh filling carrier to the shuttle when the shuttle again reaches the filling replenishing box.

In view of the fact that no filling may be 75 laid in the shed by the shuttle when it is picked from the non-replenishing to the replenishing box after detection of filling failure by the filling replenishing detector, it is 80 desirable that take-up be suspended. To this end the shaft 27, Fig. 2, has secured thereto an arm 43, the rearwardly extending end portion of which is provided with a yoke 44 which is adapted to lift the pawl carrier 17 when the shaft 27 is rocked contra-clockwise, 85 Fig. 2, to thereby render the feed pawl 18 inactive.

Mounted upon the loom frame at the replenishing side of the loom is the stopping detector B which, in the present instance, 90 comprises the weft or filling fork 45 pivotally mounted at 46 on the slide 47 and having a tail piece 48 adapted to engage a hook 49 of the weft fork or cam follower 50 when the weft or filling fork fails to be tilted on 95 a detecting beat. The slide 47 is mounted upon the stand 51 and its front end portion at 52 bears against the end of an arm 53 which is loosely mounted upon the shaft 27.

When the stopping detector detects failure of filling, it is desirable that take-up be suspended, and if the pawl carrier 17 has just operated the ratchet wheel 15, it is desirable to let the wheel back a tooth. To this end the hub portion 54 of the arm 53 105 carries a member 55, the end 56 of which is connected by a link 57 to the check pawl 58, the end 59 of which normally rides on the teeth of the ratchet wheel 15. Associated with the hold pawl 58 is the let-back pawl 60 which may be of usual construction and has, in the present instance, a slot 61 which engages the pin 62 which serves as a mounting for the holding or check pawl 58, the construction being such that when the holding or check pawl 58 is disengaged from the teeth of the ratchet and the actuating pawl carrier 17 is on its backward stroke, the let-back pawl 60 will permit the ratchet wheel 15 to let back one tooth.

Loosely mounted on the transfer or rock shaft 27 is a sleeve 63 which extends transversely of the loom and has secured to it at the non-replenishing side of the loom, in this instance, a knock-off finger 64, the upper portion of which extends laterally and backwardly as at 65, and has its end portion turned downwardly at 66 back of the knock-off lever 67 which, as shown, is pivoted at 68 to the shipper stand 69.

The shipper 70 for disengaging the power from the loom may be of usual construction and control the well-known brake mechanism in order to bring the loom to rest 5 promptly when the shipper is disengaged from its holding notch 71.

The purpose of the stopping detector B is to effect loom stoppage after two or three or more detections of filling failure by the 10 stopping detector, with the shuttle in the replenishing box, in order that the filling replenishing detector A may, between two or more detections by the stopping detector, 15 position the replenishing mechanism for effecting replenishing of filling in the shuttle on the first beat-up movement of the lay when the loom is again started.

In the present instance of the invention the slide 47 of the stopping detector has 20 mounted for rotative movement thereon the toothed tumbler 72 supported upon a lug 73 rising from the slide 47. The toothed tumbler 72 has a series of teeth 74 and one deep recess 75. Pivotally supported on the 25 slide 47 is the stop member 76 which is provided with a lug 77 adapted to ride over the teeth of the tumbler. In the present instance the stop member 76 is pivotally supported upon the lugs 78 and has a rearwardly extending portion 79 adapted to be engaged by the cam follower 50, and the parts heretofore described may be substantially the same as the corresponding parts shown in the 30 patent to Northrop, No. 1,186,933, June 13, 1916.

The toothed tumbler 72 has connected to it a governor 80 having an overweighted portion 81 which, when the parts are in normal position as indicated in Fig. 2, rests 40 upon the top surface of the slide 47. The governor 80 is connected to the tumbler in the present instance, to permit relative adjustment of the tumbler and governor for the determination of the number of filling 45 failure detections by the stopping detector that should be necessary to stop the loom with the shuttle in the replenishing box. As shown, the hub portion of the governor 80 is mounted upon the stud or shaft 82 extending laterally from the tumbler and has a 50 series of holes 83 which permit the governor to be connected to the shaft 82 of the tumbler in different relative positions by means such as a cotter pin 84, the construction being 55 such that by adjustment of the governor relative to the tumbler, the number of detections of filling failure by the stopping detector may be varied to bring the loom to stop on the second, third or fourth detection 60 of filling failure by the stopping detector, as will now be described.

Secured to the transversely extending sleeve 63 is an arm 85, Fig. 2, which has pivotally connected thereto the tumbler rotator 65 and stopping finger 86, the end portion 87 of

which is normally in position to engage a tooth of the tumbler as the tumbler is moved frontwardly with the slide 47 on detection of filling failure by the stopping detector. The stopping member 76 has a face portion 70 88 which, when it is allowed to drop by the projection 77 of the stopping member entering the deep notch 75 of the tumbler, comes into the path of the end portion 87 of the tumbler rotator and stop finger 86, and by 75 frontward movement of the slide 47 causes the sleeve 63 to be rocked to effect loom stoppage through the knock-off lever 67.

The number of step rotative movements to be imparted to the tumbler 72 to permit the 80 face portion 88 of the stopping member 76 to drop to its lower position, as indicated in Fig. 4, may be varied by adjusting the governor 80 relative to the tumbler 72.

If it be desired to stop the loom with the 85 shuttle in the replenishing box on the second detection of filling failure by the stopping detector, the governor 80 is connected to the tumbler 72 to hold the tumbler in position with the projection 77 of the stopping member 90 76 resting on the teeth of the tumbler next to the deep recess 75, so that on the first detection of filling failure by the stopping detector as the shuttle enters the replenishing box, the slide 47 will be moved front- 95 wardly by the weft hammer 50 to cause the finger 86 to engage a tooth of the tumbler and turn it one tooth, whereupon the projection 77 of the member 76 will drop into the deep recess 75 of the tumbler and the 100 face 88 of the member 76 will be lowered into position to engage the end of the finger 86 on the next frontward movement of the slide. If, therefore, the stopping detector again detects filling failure on a detecting 105 beat with the shuttle in the replenishing box, the face 88 of the member 76 will engage the end of the finger 86, turn the sleeve 63 and knock off the shipper, with the result that the loom will stop with the shuttle in 110 the replenishing box.

When the loom is started again after being stopped by the stopping detector, the cam follower 50 upon moving frontwardly strikes the end portion 79 of the stop member 76 and rocks the forward end of the stop member upwardly to lift the projection 77 thereof out of the deep notch 75, whereupon the toothed tumbler 72 rotates to its normal position, shown in Fig. 2, under the action of the weighted governor 80. 115

Between the first and second detections of filling failure by the stopping detector, the shuttle has been picked to the non-replenishing side of the loom and consequently on the next beat-up movement of the lay the filling replenishing detector A detects filling failure and thereupon positions the dog 37 to effect transfer when the shuttle again is picked to the replenishing box. As the 125 130

lay moves frontwardly, however, with the shuttle in the replenishing box the stop detector detects filling failure and stops the loom before the lay has completed its full 5 forward movement. The loom is now stopped with the shuttle in the replenishing box and the replenishing mechanism positioned to effect transfer as soon as the loom is again started without any attention 10 on the part of the weaver, as heretofore necessary when the loom was stopped with the shuttle in the non-replenishing box.

In accordance with the present invention, the weaver is relieved from duties heretofore required when the loom was stopped 15 with the shuttle in the non-replenishing box, as is the usual custom, and when the loom is again started after having been stopped by the stopping detector, a fresh filling carrier is at once transferred to the shuttle as 20 the lay completes its forward movement and weaving continues with full picks of filling laid in the shed.

What is claimed is:

25 1. In a filling replenishing loom, the combination of a weft or filling fork detector mechanism at the non-replenishing side of the loom, replenishing mechanism controlled by the said detector mechanism to 30 transfer a fresh supply of filling to the shuttle when the latter reaches the replenishing side of the loom following detection of filling failure by the said detector mechanism, a second detector mechanism at the 35 replenishing side of the loom, and stopping mechanism controlled by the second detector mechanism to stop the loom with the shuttle in the filling replenishing box and the replenishing mechanism positioned to 40 effect replenishment of filling on the first forward movement of the lay following loom stoppage.

2. In a filling replenishing loom, the combination of a filling replenishing detector 45 at one side of the loom, a stopping detector at the opposite side of the loom, filling replenishing mechanism controlled by the filling replenishing detector, stopping mechanism controlled by the stopping detector, 50 and means for causing the stopping detector to stop the loom through the stopping mechanism with the shuttle in the filling replenishing box only after a predetermined number of filling failure detections by the 55 stopping detector and after the filling replenishing detector has positioned the replenishing mechanism to effect a transfer of filling to the shuttle on the first beat-up movement of the lay when the loom is again started, and means for suspending the take-up when either detector detects filling failure. 60

3. In a filling replenishing loom, the combination of a filling replenishing detector at one side of the loom, a stopping detector at the opposite side of the loom, filling 65 replenishing mechanism controlled by the

filling replenishing detector, stopping mechanism controlled by the stopping detector, including a knock-off lever for releasing the shipper, a filling fork carrying slide, a rock shaft having an arm rigid therewith and 70 adapted to be actuated by the movement of said slide, a second arm rigid with said shaft and positioned to impart movement of the slide to the knock-off lever to release the shipper, and means upon said slide and 75 controlled by the stopping detector to actuate the first mentioned arm to stop the loom only after a predetermined number of filling failure detections by the stopping detector. 80

4. In a filling replenishing loom, the combination of a detecting mechanism at the non-replenishing side of the loom for effecting replenishment of filling on the first detection of filling failure on a detecting beat, a second independent detector mechanism at the replenishing side of the loom for stopping the loom operation, and a stopping mechanism controlled by the second detector mechanism to stop the loom on the occurrence of a predetermined number of filling failures when the shuttle is in the box at the replenishing side of the loom and the replenishing mechanism is positioned for replenishment of filling on the first beat-up movement of the lay following loom stoppage. 90

5. In a filling replenishing loom, the combination of a filling replenishing detector at one side of the loom, a stopping detector at the opposite side of the loom, filling replenishing mechanism controlled by the filling replenishing detector, stopping mechanism controlled by the stopping detector, and means for causing the stopping detector to stop the loom through the stopping mechanism with the shuttle in the filling replenishing box only after a predetermined number of filling failure detections by the stopping detector and after the filling replenishing detector has positioned the replenishing mechanism to effect a transfer of filling to the shuttle on the first beat-up movement of the lay when the loom is again started, and means for suspending the take-up when either detector detects filling failure. 100

6. In a filling replenishing loom, the combination of a filling replenishing detector at the non-replenishing side of the loom, replenishing mechanism including a dog which is positioned by the said detector upon detection of filling failure to effect replenishment of filling when the shuttle is in the replenishing box, a stopping detector at the replenishing side of the loom, stopping mechanism for stopping the loom with the shuttle in the replenishing box upon the occurrence of a plurality of filling failures by the stopping detector and at least 110 115 120 125 130

one failure of filling by the filling replenishing detector that the loom may be stopped with the dog positioned to effect replenishment of filling on the first beat-up 5 movement of the lay following loom stop page.

7. In a filling replenishing loom, the combination of filling replenishing mechanism including a dog, a filling replenishing detector at the non-replenishing side of the loom, connection between said detector and dog for operatively positioning the latter when the said detector detects filling failure on a detecting beat, a stopping detector at 10 the replenishing side of the loom, means including a shipper actuated by the stopping detector to stop the loom upon detection of filling failure a determined number of times in succession by the stopping detector and 15 at least once by the filling replenishing detector that the loom may come to rest with the shuttle in the replenishing box and the dog positioned for actuating the replenishing mechanism when the loom is again 20 started.

8. In a filling replenishing loom, the combination of filling replenishing mechanism including a dog, a filling replenishing detector at the non-replenishing side of the loom, connection between said detector and dog for operatively positioning the latter when the said detector detects filling failure on a detecting beat, a stopping detector at 25 the replenishing side of the loom, means including a shipper actuated by the stopping detector to stop the loom upon detection of filling failure a determined number of times in succession by the stopping detector and at least once by the filling 30 replenishing detector that the loom may come to rest with the shuttle in the replenishing box and the dog positioned for actuating the replenishing mechanism when the loom is again started, and means for 35 suspending take-up upon detection of filling failure by either detector.

9. In a filling replenishing loom, the combination of filling replenishing mechanism including a dog, a filling replenishing detector at the non-replenishing side of the 40

loom, connection between said detector and dog for operatively positioning the latter when the said detector detects filling failure on a detecting beat, a stopping detector at the replenishing side of the loom, means 45 for selectively determining the number of successive detections of filling failure by the stopping detector necessary to render it effective to stop the loom, means including a shipper actuated by the stopping detector to stop the loom upon detection of filling failure a determined number of times in succession by the stopping detector and at least once by the filling replenishing detector that the loom may come to rest with 50 the shuttle in the replenishing box and the dog positioned for actuating the replenishing mechanism when the loom is again started.

10. In a filling replenishing loom, the combination of filling replenishing mechanism, a filling replenishing detector at one side of the loom for operatively positioning the replenishing mechanism on detection of filling failure, a stopping detector at the 55 opposite side of the loom, comprising a toothed tumbler, a governor, means for varying the number of tumbler movements necessary to render the stopping detector effective to stop the loom, and a shipper 60 which is actuated by the stopping detector to stop the loom when the tumbler has made the predetermined number of movements.

11. In a filling replenishing loom, the combination of filling replenishing mechanism, means for replenishing the filling on filling failure, a stopping detector including a tumbler, a governor, an adjustable connection between the tumbler and governor for varying the number of tumbler 65 movements necessary for rendering the stopping detector effective, and stopping mechanism actuated by the stopping detector to stop the loom when the tumbler has been given the predetermined number of 70 tumbler movements.

In testimony whereof, I have signed my name to this specification.

THOMAS E. NORMAN.
